NON-COMBUSTIBLE TRASH AND WASTE PAPER CONTAINER

Daniel Subarsky, Springfield, Mass., assignor to Albert Fine, Baltimore, Md.

Application August 1, 1955, Serial No. 525,561

6 Claims. (Cl. 169—2)

This invention relates to containers for trash and waste paper, and more particularly to a lid attachable to a portable can or conventional container used for holding waste paper and other combustible trash, that will tend to overcome or reduce combustion arising from spontaneous combustion or accidental firing.

A frequent cause of fire arises from those started in waste-baskets and other open industrial or domestic containers used for holding scrap paper and other combustible waste material. A cigarette, match or cloth smoldering dropped in the material becomes, in many instances, a blazing mass of flames, that can do considerable damage. So many fires are induced in this manner throughout the country, that it is considered a major cause of such happenings. The problem has not been solved in the devices already provided and considered for it. However in the matter of cigarettes and the like, devices have been designed and made to extinguish them while resting on a bottle-like ash tray by using a holder for the cigarette with its burning end suspended over the chamber within the tray and allowing it to burn itself out. This arrangement however would not be suitable for a modern waste-basket or trash receiver of metal, as it would not extinguish a fire therein. In this invention, the main principle involved is that employing means for diverting a circulation of air within the container and rendering same stagnant and deficient in oxygen so the combustion is slowed up and eventually overcome and the fire automatically extinguished. This is accomplished through the use of an open and removable lid or crown placeable on the open top of the container, planned to obstruct any circulation of air that would support combustion, and thereby extinguish it.

The invention includes in its objects the provision of a new and improved trash receiver that will overcome one or more, of the disadvantages and limitations of the prior art.

Another object of the invention is to provide a new and improved lid for a trash receiver that will deprive the container of an amount of fresh air that will be necessary to support combustion within it, if a fire should be started in it.

A further object of the invention is to provide a new and improved trash can or waste materials basket that will be self-extinguishing, if combustion is started within it.

Other objects of this invention are to provide a new and improved trash container assembly that will be simple in structure, economical to manufacture, easy to assemble and effective in function, when used for holding combustible material usually found in trash, and upon being susceptible to unauthorized ignition the arrangement of the parts of the assembly being adapted to bring about an adverse composition of the air within, that will bring about an extinction of a fire arising in it, within a short time.

Still another object of the invention is to provide a new and improved smothering crown for a trash con-

2

tainer, that will divert the gases arising from combustion within it back over the burning material and extinguish it with the gases as they develop into CO₂.

Other objects of the invention will be apparent as it is more fully described.

For a better understanding of the invention and its objects, reference is made to the accompanying drawings wherein a particular form of the invention is illustrated, the description of which follows:

10 In the drawings:

Figure 1 is a plan view of a trash receiver embodying this invention;

Figure 2 is a side elevation of Figure 1;

Figure 3 is a bottom view of the lid or smothering crown used in this embodiment; and

Figure 4 is a sectional elevation taken on line 4—4 of Figure 1, with the removable crown, shown half in section and half in full.

Similar reference numerals pertain to the same parts throughout the drawings.

In the structure shown in the drawings there is shown a container 10 of non-combustible material which is designed to hold trash and waste paper, and it follows conventional form in a general way. Its height from its bottom to its top rim, is twice the diameter, both dimensions being taken on the inside of the container. It is preferably of cylindrical shape with its walls 11 reinforced at the bottom by a ring 12 which serves to keep it off the ground and provide an air space 13 underneath.

25 A removable lid 14 is provided for the top of the container 10 and it is arbitrarily termed a smothering crown. It is made of relatively thin and flat material formed in two frustumal upper and lower sections 15 and 16, respectively, joined tightly together where their wide rims 17 meet, and with circular openings 18 and 19 respectively provided at their restricted diametrical rims 20 and 21. This leaves a chamber 22 within the walls shaped like that of two inverted cones (See Fig. 4). The openings 18 and 19 are similar in size and form, and are equal to substantially one-half of the inside diameter of the container 10.

30 The upper section 15 has a downwardly directed collar 23 at its opening 18 and the rim nearby is reinforced with a thin ring 24. The collar 23 is made deep enough to interfere with the draft induced along the tapering inside surface of the upper section and obstruct its emission through the opening 18. The lower section 16 has a series of aligned and spaced small holes 25 in its tapered wall, located half way up. The size of these holes 25 increases from $\frac{1}{2}$ " diameter spaced 2" apart for a 12" inside diameter container to those of larger diameter in approximately direct proportion.

35 The rims 17 of the smothering crown 14 are arranged with a peripheral flat portion 26 adapted to rest on the upper rim of the container 10 and, in addition, a collar 27 running annularly within the portion 26 extends down about $\frac{3}{4}$ " to hold the crown 14 in place and seal it loosely to the container 10. This arrangement permits the crown to be put in place readily and also with the sections in the proper working position. This is necessary as the device will not work as intended, otherwise. The sections are substantially symmetrical.

40 The inwardly upward converging wall of the lower section 16 serves as a trap for drafts occurring within the container. It also restricts the chimney outlet. When combustion takes place in the container 10, the heated air and chemically combined products of combustion tend to rise through the lower middle opening 19 into the chamber 22 and circulate down through the holes 25, together with cold outer air coming down through the opening 18. The combustion is completed and CO₂ formed. The latter as it circulates through and over the burning

trash smothers it, reduces the burning, and eventually puts the fire out. The collar 23 diverts the burning gases down along the diverging wall of the upper section towards the rim 17, where it bends to follow the converging wall of the lower section and through the holes 25. The gases continue down peripherally along the wall 11 of the container and then curves to come up through the central area. This continues until the combustion is stopped.

The device is easy to handle. It is open at the top so as not to interfere with the usual loading of waste into it. Its appearance is attractive. It can be emptied quickly. In case water or other non-combustible liquid is needed to apply to the burning material within it, such can be applied without removing the smothering crown, and the form of the latter and the holes 25 in it facilitate this application and enables the crown to be cooled off.

In the operation of the invention, carbon dioxide which consists of twelve parts of carbon, and thirty two parts of oxygen is an excellent fire extinguisher. A chemical action is created when a fire starts in the container with a free current of air. Carbon monoxide, which consists of twelve parts of carbon, and sixteen parts of oxygen, is produced when the substance or material in the container is being consumed. The crown or lid will cut off most of the oxygen supply. The existing oxygen, and the carbon monoxide creates the carbon dioxide, which is forced down by the series of holes 25 in the lower section 16, thus causing a back draft and extinguishing the fire.

While but one general form of the invention is shown in the drawings and described in the specification, it is not desired to limit this application for patent to this particular form as it is appreciated that other forms of construction could be made that would use the same principles and come within the scope of the appended claims.

Having thus described the invention, what is claimed is:

1. A trash container comprising in combination, a container open for its full area at the top rim thereof, a removable smothering crown placeable on said rim and fitting closely thereto, said crown consisting of a pair of sections having converging walls joined together at their outer peripheries and open to half their width at the inner peripheries, the sections being fitted to the top of the container on their outer peripheries in a horizontal position and with holes in one of the sections to promote the circulation and recirculation of gases within the container in predetermined directions.

2. A trash container comprising in combination, a container open for its full area at the top rim thereof, a removable smothering crown placeable on said rim and fitting closely thereto, said crown consisting of a pair of sections having converging walls joined together at their outer peripheries and open to half their width at the inner peripheries, the sections being fitted to the top of the container on their outer peripheries in a horizontal position and with holes in one of the sections to promote the circulation and recirculation of gases within the container in predetermined directions, said holes being aligned and spaced and relatively small and located in the wall of the section selected on a line outside the width of said openings so that the circulating gases will tend to flow up centrally in the container and through said openings and return through the said holes close to the wall of the container.

3. A trash container comprising in combination, a container open for its full area at the top rim thereof, a removable smothering crown placeable on said rim and fitting closely thereto, said crown consisting of a pair of sections having converging walls joined together at their outer peripheries and open to half their width at the inner peripheries, the sections being fitted to the top of the container on their outer peripheries in a horizontal position and with holes in one of the sections to promote

the circulation and recirculation of gases within the container in predetermined directions, said sections being substantially symmetrical and forming an internal contour similar to that of two inverted cones; said sections being disposed one above the other in upper and lower relation; the lower section having the said holes therein located approximately one-half the distance on the converging wall between its opening and the said rim.

4. A trash container comprising in combination a container open for its full area at the top rim thereof, a removable smothering crown placeable on said rim and fitting closely thereto, said crown consisting of a pair of sections having converging walls joined together at their outer peripheries and open to half their width at the inner peripheries, the sections being fitted to the top of the container on their outer peripheries in a horizontal position and with holes in one of the sections to promote the circulation and recirculation of gases within the container in predetermined directions, said sections being substantially symmetrical and forming an internal contour similar to that of two inverted cones, said sections being disposed one above the other in upper and lower relation, the lower section having the said holes therein located approximately one-half the distance on the converging wall between its opening and the said rim, the height of the container being regulated by the internal width thereof and approximately twice the internal diameter.

5. A trash container comprising in combination, a container open for its full area at the top rim thereof, a removable smothering crown placeable on said rim and fitting closely thereto, said crown consisting of a pair of sections having converging walls joined together at their outer peripheries and open to half their width at the inner peripheries, the sections being fitted to the top of the container on their outer peripheries in a horizontal position and with holes in one of the sections to promote the circulation and recirculation of gases within the container in predetermined directions, said sections being substantially symmetrical and forming an internal contour similar to that of two inverted cones; said sections being disposed one above the other in upper and lower relation, the lower section having the said holes therein located approximately one-half the distance on the converging wall between its opening and the said rim, the height of the container being regulated by the internal width thereof and approximately twice the internal diameter, the upper section including a downwardly directed collar for facilitating the downward movement of circulation through the peripheral area of the container and crown and continuing upwardly through the said opening in the central area of the container and sections.

6. A trash container comprising in combination a container open for its full area at the top rim thereof, a removable smothering crown placeable on said rim and fitting closely thereto, said crown consisting of a pair of sections having converging walls joined together at their outer peripheries and open to half their width at the inner peripheries, the sections being fitted to the top of the container on their outer peripheries in a horizontal position and with holes in one of the sections to promote the circulation and recirculation of gases within the container in predetermined directions, said sections being substantially symmetrical and forming an internal contour similar to that of two inverted cones, said sections being disposed one above the other in upper and lower relation, the lower section having the said holes therein located approximately one-half the distance on the converging wall between its opening and the said rim, the height of the container being regulated by the internal width thereof and approximately twice the internal diameter, the upper section including a downwardly directed collar for facilitating the downward movement of circulation through the peripheral area of the container and

crown and continuing upwardly through the said opening in the central area of the container and sections, and means for facilitating the placement of the crown on the rim of the container and its removal therefrom.
